UNITED STATES PATENT OFFICE

WALTER O. CRITCHFIELD, OF SHELBY, OHIO, ASSIGNOR TO SHELBY SALESBOOK COMPANY, OF SHELBY, OHIO

TISSUE HOLDER FOR SALES BOOKS

Application filed March 24, 1928. Serial No. 264,453.

This invention relates to a sales book and is especially intended to form a convenient holder for sheets of tissue forming original copies of sales transactions simultaneously made with a carbon copy thereof for auditing purposes. The invention is especially intended to make more convenient for the salesman the management of the tissue copy, at the time of the sale. To this end the invention consists of a clamp mounted in the sales book on a convenient support in which may be inserted a pad of auditor's slips with a superposed sheet of double-faced carbon paper and along the side of the clamp is a vertical support forming a holder for a tissue book, the back cover of which is conveniently mounted between a fixed vertical guide and a pivoted spring arm, adapted to swing into a vertical plane to admit the back of the tissue book and then swung down in parallelism with the supporting strip to clamp it in place. Thus the pages of the detachable tissue are very conveniently supported adjacent to the carbon sheet and may be swung over into engagement with the block of auditor's checks one page at a time to form an original copy of the sale.

My construction provides also a folding lid by which the tissue book cover may be snugly held when the book is not in use, so as to protect the pages from mutilation. The several features of novelty will be more fully hereinafter described and will be definitely indicated in the appended claims.

In the accompanying drawings illustrating the invention:—

Figure 1 is a plan of a sales book cover embodying the invention.

Figure 2 is a median transverse section.

Figure 3 is a plan of the sales book containing the tissue holder ready for recording a sale.

Figure 4 is an isometric view of a retainer for the carbon tissue book.

Figure 5 is a median vertical section.

Referring now in detail to the drawings, I preferably provide an outside cover composed of three foldable parts, the structure of which will be clearly apparent from an inspection of Figures 2 and 5. 1 represents

the outside cover, 2 the back cover and 3 a foldable inside cover to form a convenient clamping means for the back of the tissue book. I preferably form at the hinged section of the book cover, a thin portion flexibly adapted for opening and closing.

A book of thin tissue paper pages which form the original record of the sale as indicated at 8, is mounted on a stout paper cover 7, the back of which 7^a is adapted to pass over a clamp, hereinafter to be described, and lie beneath the folding back 3, in which position it will be snugly and smoothly held. The pad of auditor's checks is superposed on the folding section 3 of the cover, as indicated at 4 in Figures 2 and 5 and is maintained in fixed relation by spring clamp 5, riveted to the top side of the outer section of the cover 3, this clamp having a spring pressed lid 5 with clamp jaws on its top and bottom transverse edges, side and a thumb piece 6 of depressed metal to afford a convenient means of lifting the spring lid to mount the block of auditor's checks. At right angles to the spring clamp of the auditor's checks, along the longitudinal edge of the fold of lid 1 is a holder for the tissue book, the structure of which will be clearly apparent from inspection of Fig. 4. This consists of an angular strip of sheet metal 10^a, provided with holes by which it may be riveted to the back as indicated at 9 in Figures 3 and 4 to the vertical edge 10—10^a on which is riveted at one end as indicated at 11, a strip of spring sheet metal 12 having a longitudinal stiffening rib 13 and carrying at the free end a clamp button 14, adapted to enter a slot 15 in the edge of the angle bar and form a retainer for the back of the tissue book as will be clearly apparent from a consideration of Fig. 2. By unlocking the button 14 the strip 12 springs away from the slot 15 and the strip may be swung up at right angles to permit convenient admission for the bottom cover of the tissue book and swung back to a horizontal position and latched by the button 14. The top cover of the tissue book 7^a is securely retained in its position by the pressure of auditor's checks on the folding section 3 of the book cover.

The spring support for the auditor's check 100

is riveted to the top of the outer section 3, as illustrated in Fig. 1, so that when the book is folded in operative position to effect a sales transaction a tissue sheet may be laid over the block of auditor's checks as indicated in Figures 2 and 3 in position for recording a sale. The section of the cover carrying the clamp 5 is provided on one edge with an angular strip of metal 18, which forms a convenient grip in handling the book to attach and detach the tissue book. The tissue book will preferably have as many pages as the pad of auditor's reports and are preferably so bound in cover as to be readily detachable one at a time, each auditor's check to be of double length so that its bottom side may be folded to overlie a carbon sheet and a tissue page may be applied over said carbon sheet in a manner similar in a common form of salesman's check books. The form of book as thus described forms an unusually convenient means of preserving a record of sales transactions for a supply house with a minimum danger of damage to the tender tissue or the original copy and permits great expedition in the transaction of sales.

Having thus described my invention, what I claim is new and desire to secure by Letters Patent is:

30. 1. A tissue book holder for manifolding books comprising a pair of clamping jaws one of which is adapted to be rigidly secured to the back of the manifolding book, the other jaw being formed of resilient material, means to connect one of the ends of the jaws to permit of pivotal movement of the resilient jaw at right angles to the back of the manifolding book and flexing said resilient jaw in a plane parallel with said back, and means to detachably connect the other ends of the jaws to clamp the tissue book between said jaws.
35. 2. A tissue book holder for manifolding books comprising a pair of clamping jaws one of which is adapted to be rigidly secured to the back of the manifolding book and having an elongated opening therein, and the other jaw being formed of resilient material, means to connect one of the ends of the jaws to permit of pivotal movement of the resilient jaw in a plane parallel with the rigid jaw, and a pivotally mounted clamping button carried by one jaw for passage through the opening of the other jaw to detachably engage said other jaw to hold the jaws in clamping position.
40. 3. A tissue book holder for manifolding books comprising a pair of clamping jaws including an upwardly extending jaw adapted to be rigidly secured to the back of the manifolding book, the other jaw being formed of resilient material, a pivot pin extending transversely through one end of the jaws to connect the latter and permit of pivotal movement of the resilient jaw in a plane parallel with the upwardly extending jaw, and means

to detachably connect the other ends of the jaws to clamp the tissue book between said jaws.

In testimony whereof I affix my signature.

WALTER O. CRITCHFIELD.
